UNITED STATES PATENT OFFICE.

AARON NICHOLSON, OF ALBANY, NEW YORK.

VALVE-GEAR FOR STEAM-ENGINES.

SPECIFICATION forming part of Letters Patent No. 514,024, dated February 6, 1894.

Application filed December 14, 1892. Serial No. 455,136. (No model.)

To all whom it may concern:

Be it known that I, AARON NICHOLSON, of the city and county of Albany, in the State of New York, have invented new and useful Improvements in Steam-Engines, of which the following is a specification.

My invention relates to improvements in valve-gear for steam engines, but especially to steam engines of the Corliss type provided with disengaging steam-valves which are utilized for cutting-off the steam so as to have it operate expansively; in the usual form of valve-motion used on the Corliss type of engines the disengagement of the steam-valves is effected while said valves are making their opening movement, and, for that reason, the disengagement occurs when the engine is at half-stroke, or before it has attained the half-stroke point.

The object of my invention is to provide facilities for increasing the range of expansion in the Corliss type of engines, and to automatically vary the point of cutting-off to correspond to the duty that the engine is required to perform. This object I attain by the means illustrated in the accompanying drawings, which are herein referred to and form part of this specification.

In said drawings, Figure 1 is a side elevation of the parts of the steam engine affected by my invention, some of the parts being removed to show underlying parts. Fig. 2 is an end elevation of the same with a part of the rim of the governor-wheel broken out to show parts of the governor; and Fig. 3 is a detached side elevation of the cylinder and valve-connections.

As represented in the drawings, A designates the cylinder of the steam engine, which is of the ordinary Corliss type and provided with the usual oscillating form of valves used in that type of engine. Of said valves, the two steam-valves, 1, are arranged to operate independently of each other by being tripped from their operating mechanism. The two exhaust-valves, 2, are preferably connected together by a yoke, 3, so as to be moved simultaneously. Each of said steam valves has a bell-crank, 4, secured to its stem which projects through a stuffing-box, 5, and to the horizontal arm of said bell-crank a rod, 6, is jointed, said rod being connected to the plun-

ger of a dash-pot, 7, which is provided for the purpose of governing the closing movement of said valve. To the other arm of each bell-crank there is pivoted a toe, 8, which is normally depressed by means of a spring, 9, to hold the free end of said toe in a required position. The yoke 3 is provided with a slotted opening, 10, for the purpose of allowing said yoke to travel in a curved path to accord to the arc prescribed by the wrist-pins, 11, in the arms, 12, secured to the outer end of each exhaust-valve 2. When preferred a rod jointed in its middle to connect to a wrist-pin moving in a direct line may be substituted for the slotted yoke.

B designates the main eccentric by which the opening movement of the steam-valves and the opening and closing movements of the exhaust-valves are effected; said eccentric is secured to the engine-shaft 13 in a position to give a required lead to the opening movements of the steam- and exhaust-valves, and it is connected—by an eccentric-rod, 14—75 to a tripper-slide, C, which is fitted to move in a guide, 15, on the side of the cylinder A; said tripper-slide is provided with a pair of tripers, 16, which are pivoted, as at 17, to said slide so that the engaging end of the two tripers will be faced in opposite directions; the opposite end of each tripper is beveled or rounded, as at 18, and is provided with a stud, 19, against which a spring, 20, takes to normally retain that end of the tripper in a depressed position.

D designates a governor, of which I do not claim to be the inventor, which is secured to the engine-shaft 13; said governor consists of a pair of weighted-arms, 21, pivoted to the 90 governor and connected to springs, 22, which normally retain said arms in their closest position to the shaft 13; said weighted arms are connected, by rods, 23, to oppositely-located arms, 24, of a sleeve, E, which is loosely fitted 95 on the shaft 13, so as to be oscillated on the latter.

F designates the cut-off eccentric which is secured to the sleeve E, and is rotated by the shaft 13; said cut-off eccentric is connected—100 by a rod, 25—to a sliding cam-plate, G, that is fitted to slide in the tripper-slide C, and is provided with oppositely-inclined cam-faces, 26, which are fitted to engage with the rounded

ends of the trippers 16 and effect a tilting movement of the latter on the pivots 17. A face-plate, 27, is secured to the tripper-slide C and is provided with slotted - openings, 28, through which the studs 19 are moved. The springs 20 are preferably secured to said face-plate adjacently to said slotted-openings, and a pendent arm, 29, attached to the tripper-slide C, is provided with a wrist-pin, 30, which engages in the slotted-opening, 10, of the yoke 7 for the purpose of imparting a reciprocating motion to said yoke.

My invention operates in the following manner: Premising that the engine is started in motion with the weighted-arms 21 in the position shown in Fig. 1, so that the cam-plate G will not effect a disengagement of the tripper 16 from the toe 8 with which it is engaged at the time, for the reason that the two eccentric 15 are then in substantially the same position in respect to the throw of said eccentrics; as the engine increases its speed said weighted-arms will be moved, by centrifugal force, to swing farther from the shaft 13, and therefore 20 by the sleeve E will be partially rotated to advance the throw of the eccentric F in respect to the throw of the eccentric B, and, as a consequence, the cam-face 26 nearest the open steam-valve, will be quickly carried into 25 contact with the rounded end of the corresponding tripper 16 and effect a tilting movement of the latter that will disengage said tripper from the toe 8 and allow the weight of the rod 6 and its appendages to effect the 30 closing movement of said steam-valve; the variation in the point of cutting off the steam being dependent upon the position in which 35

the eccentric is automatically set by the action of the governor D.

I am aware that steam-engines have heretofore been constructed with independently operating steam and exhaust valves, but the tripping-mechanism for releasing the steam-valves was substantially different from mine and operated in a different manner; and I am also aware that Patent No. 329,288 shows a steam-engine having two detachable valves which govern both the admission of steam and the exhaust of the same, so that the exhaust-ports will be closed simultaneously with the closing of the steam-ports to effect the cutting-off of the steam, thereby producing an objectionable degree of compression of steam, which will detract from the power of the engine. I do not claim either of said constructions; but

What I claim as my invention, and desire to secure by Letters Patent, is—

In a steam engine, the combination with a tripper-slide, C, having a pair of tilting trippers, 16, pivoted thereto and arranged to take against arms, 4, secured to the oscillating steam-valves; said tripper-slide being connected—by a yoke 3—to the arms 12 secured to the oscillating exhaust-valves, of a sliding cam-plate, G, fitted to reciprocate in the tripper-slide and provided with cam-faces, 26, arranged to tilt said trippers, as and for the purpose specified.

AARON NICHOLSON.
